UNITED STATES PATENT OFFICE.

PETER SIVERTSEN, OF NEW YORK, N. Y., ASSIGNOR TO GLOBE SLICING MACHINE CO. INC., OF NEW YORK, N. Y., A CORPORATION OF NEW YORK.

SLICING MACHINE.

Application filed August 22, 1919. Serial No. 319,059.

To all whom it may concern:

Be it known that I, PETER SIVERTSEN, a subject of the King of Norway, residing in the city of New York, county of Bronx, and 5 State of New York, have invented certain new and useful Improvements in Slicing Machines, of which the following is a specification.

My invention relates to slicing machines 10 and has more special reference to a machine in which the object is advanced by its own weight toward a knife which is moved at least during the cutting operation. The arrangement for advancing the object may and 15 preferably does take the form of an inclined reciprocative feedway, as shown in the illustrated embodiment, down which the object slides freely, thereby obviating the necessity for clamping elements and permitting the 20 objects to be more readily changed in the feedway, simplifying the construction and because of the elimination of the clamping elements permitting the object to be entirely cut up.

25 My invention further provides an arrangement whereby the cutting edge is effectually guarded, the central portion of the guarding member being stationary and serving as an aid to prevent displacement of the object during the cutting operation.

Other objects and advantages will appear from the following description and appended claims.

The drawings accompanying this specification and forming a part thereof illustrate 35 two embodiments of my invention in which:

Figure 1 is a side elevation of my apparatus.

Fig. 2 is a fragmentary end elevation of 40 the apparatus, showing a cutting mechanism and its appurtenances, partly in section.

Fig. 3 is a fragmentary end view of the tray regulating mechanism partly in section.

Fig. 4 is a fragmentary top plan view of the apparatus, on the plane 4—4, of Fig. 2.

Fig. 5 is a fragmentary side elevation of a modification of my feeding mechanism.

Referring to the drawings and particularly to Figs. 1 to 4, a base plate 10, is provided with an upwardly projecting sleeve 11, preferably integrally formed with the base plate, and adapted to receive an extension piece or reduced end 12, at the lower 55 end of a vertical post 13. The upper por-

tion of this post is inclined to the horizontal, preferably at an angle of 45 degrees. The inclined portion of the post 13 is of reduced diameter, forming a stub shaft 13' which carries a rotatable sleeve 14. The lower end 60 of this bearing is supported by the shouldered portion 15 of the post 13. A pulley 16 is secured to the sleeve 14, and is held in position by a set screw 17. The pulley is preferably driven by a belt 18, although obviously it may be driven by other means. The belt 18 may be actuated by any suitable source of motive power, for instance, by a small electric motor, or if found desirable, it may be hand driven. The end of the inclined portion of the post 13 has an externally threaded end 19 of reduced diameter. A circular disc 20 having an internally threaded portion 21 at its center is secured to the threaded portion of the screw 19, thus 70 forming a relatively stationary part to which the appurtenances for guarding the knife edge to be described, are secured. This disc preferably tapers from its center outwardly, so that its thickest portion is at 80 the center. The center is of such thickness as to correspond to the length of the screw-threaded portion of the end 19. A rotatable disc 22 is connected to the sleeve 14 in any suitable manner, and has an annular 85 recess or shouldered portion 23 at its peripheral edge to receive a narrow annular knife edge or blade 24. The blade 24 is secured to the disc 22 in any convenient manner, for example by screws 25. The disc 22 tapers in the manner described in connection with the disc 20, sufficient clearance being provided between the rotatable disc 22 and the stationary disc 20 to avoid 90 contact between the two. A circular guard plate 26 is attached to the stationary disc 20 by screws 27. The outer edge of this guard member is turned over so as to provide a depending annular curtain 28, projecting 95 downwardly a sufficient distance to adequately protect the knife edge 24. A portion of the guard plate 26 is cut away at A to permit the knife to engage the meat in the slicing operation.

The base plate 10 is further provided with 100 a plurality of vertical posts 29, 30, 31 and 32, the posts 29 and 30 supporting a horizontal guide shaft 33, and the posts 31 and 32 supporting a horizontal guide shaft 34. Shafts 33 and 34 are arranged parallel to 105

each other and receive the slidable bearings 35 and 36. The bearings 35 and 36 carry upwardly projecting brackets 37 and 38, connected by a transverse web 38' having a handle 39'. Each of the brackets 37 and 38 is preferably provided at its upper end with forked member 39 and 40 respectively. The forked members serve to support a feed or guide chute 41 in a position inclined to the horizontal. Obviously instead of the pair of shafts and forked brackets, a single shaft, provided with a key-way, so shaped as to prevent rotation of the bearing, might be provided for supporting the chute 41. The guide chute is of any desired shape and is inclined to the base plate as stated, preferably at an angle of 45 degrees, and so arranged that its longitudinal axis is perpendicular to the face of the cutting mechanism and is reciprocable with respect thereto by virtue of the bearings 35 and 36 sliding on the horizontal shafts 33 and 34. The base plate 10 is further provided with a vertical post 42 for carrying a meat-receiving tray which supports the end of the meat prior to its contact with the cutting mechanism, and regulates the thickness of the slices. The lower end of the post 42 is preferably provided with a boss or extension piece 43 of reduced diameter and adapted to rest in a sleeve 44, the latter being preferably integrally formed with the base plate. The upper end of the post 42 has a plurality of radial arms 46, 47, 48 and 49, each of which has a flanged end forming a bearing for shafts to be described. The bearings of the arms 46 and 47 carry a transverse shaft 49' on which a meat-receiving tray 50 is pivotally mounted by spaced downwardly depending brackets or bosses 51 and 52. The pair of arms 48 and 49 and its appurtenances, serve to support the portion of the meat-receiving tray adjacent to the cutting mechanism which is vertically movable, whereby the tray may be tilted to any desired inclination, so that its edge adjacent to the cutting mechanism may be raised or lowered to any desired extent. The bearings of the arms 48 and 49 support a transverse rotatable shaft 53 having a cam 54 secured thereto in any convenient manner and at any convenient portion thereof, the cam face engaging the lower surface of the meat-receiving tray 50. One end of the shaft 53 is provided with a handle 55, which serves to rotate the shaft 53 and its attached cam 54 to any desired extent. The rotation of the cam causes the variation in the elevation of the tray, as will be readily apparent. A spring 54' is interposed between the handle 55 and the bearing supporting the shaft 53 to frictionally prevent rotation of the shaft and cam, thus maintaining the desired elevation of the tray.

65 In the modification shown in Fig. 5, the

meat feeding tray 50, the rotary cutting knife 24 and the guard 26 are similar to those described in connection with the structure shown in Figs. 1 to 4. Instead of the shafts 33 and 34 for reciprocably supporting the feed chute and its appurtenances, a bracket 60 secured to a convenient table, supports the lower end of an upwardly projecting oscillating arm 61, in a bearing 62. The upper end of the arm 61 is provided with a forked member or bifurcated end 64 for receiving a feed trough or chute 65, which is inclined to the horizontal in any manner similar to the feed trough 41, described in connection with the structure shown in Figs. 1 to 4. A stop lug 66 is formed with the bracket 60 and limits the movement of the arm 61 and its appurtenances. A recessed boss 67 is preferably integrally formed with the arm 61, and has its major axis projecting substantially at right angles to the longitudinal axis of the arm 61. A rod or bar 68 has one end secured within the boss 67 and extends at right angles to the longitudinal axis of the arm 61. The bar 68 is screw threaded at 69 and receives a longitudinally slideable counter weight 70 which may be shifted to any desired position on the bar 68 by shifting clamping screws 71, as will be evident from the drawings. The counter weight serves to carry the arm 61 to the position shown in full in the drawings.

In operating the embodiment of my device as shown in Figs. 1 to 4, the meat to be sliced is placed in the feed chute 41, which is initially positioned opposite the meat receiving tray 50, as shown in Fig. 1. The meat will slide down the chute 41 due to its inclination until its end bears on the face of the tray 50. The end of the tray 50 adjacent to the cutting edge 24 is raised or lowered by means of the handle 55 and its attached cam 54 to a position corresponding to the thickness of the slice desired. The chute 41 is then moved by means of the handle 39' toward the right when viewed as in Fig. 1 until the slice is completely severed from the meat. The slice passes under the edge of the knife 24 and drops to a suitable receptacle, which may be placed on base 10. The rotation of the knife blade 24 is secured as has already been stated by the drive pulley 16, actuated by any suitable source of motive power. As the meat is carried across the cutting blade 24, a portion of it rests on the stationary guard member 26 which thus prevents, to a certain extent, the displacement of the meat with respect to the chute 41. The chute 41 is then brought to its initial position, and is ready to sever another slice. It is evident that, with my construction, the chute may be moved to one side, so that access may be readily had to the knife edge. This enables very small pieces to be held in the hand and thus sliced.

In operating the embodiment of my invention illustrated in Fig. 5, the meat is placed in the chute 65. It slides down the chute in a manner similar to that described in connection with the structure shown in Figs. 1 to 4. The chute 65 is then moved by means of handle 73 in a counter clockwise direction about its bearing 62 until it and the end of the meat which it holds stand opposite to the face of the tray 50. If the handle 73 is now released, the counter weight 70 will move the tray and its arm 61 in a clockwise direction until the meat engages the edge of the rotating cutting knife 24. The weight 70 will continue to force the meat against the cutting knife 24 until the slice is completely severed. The chute 65 may then be again moved to the position for cutting the succeeding slice, indicated by the dotted line in Fig. 5. The elevation of the tray 50 is controlled in a manner similar to that described in connection with the structure shown in Figs. 1 to 4. It is evident that instead of the counter weight 70, a 25 spring may be used to perform the same function. Hence, when I speak in my claims of a counter weight, I also mean to include a spring. It is further evident that oscillation of the arm 61 and the tray 65 30 may be secured directly from the source of motive power which drives the rotary cutting mechanism, by the intervention of suitable mechanism.

I claim:

1. The combination, in a slicing apparatus, of a cutting mechanism comprising a rotary knife edge, the plane of which is inclined to the horizontal and means for guiding the object to be sliced past the knife edge, to effect the cutting operation, the 40 guiding means being reciprocal in a rectilinear direction.

2. The combination, in a slicing apparatus, of a cutting mechanism comprising a rotary knife edge, the plane of which is inclined to the horizontal and gravity feeding means for guiding the object to be sliced past the knife edge to effect the cutting operation in a direction inclined to the horizontal, the gravity feeding means being reciprocal in a rectilinear direction.

3. The combination, in a slicing apparatus, of a cutting mechanism comprising a rotary knife, the plane of the knife being inclined to the horizontal and gravity feeding means for guiding the object to be sliced past the cutting mechanism to effect the cutting operation in a direction substantially perpendicular to the plane of the knife, the 55 gravity feeding means being reciprocal in a rectilinear direction.

4. The combination, in a slicing apparatus, of a cutting mechanism comprising a rotary annular knife, the plane of the knife being inclined to the horizontal and gravity

feeding means comprising a chute for guiding the object to be sliced past the cutting knife to effect the cutting operation in a direction substantially perpendicular to the plane of the knife, the gravity feeding 70 means being reciprocal in a rectilinear direction.

5. The combination, in a slicing apparatus, of a cutting mechanism comprising a rotary annular knife, the plane of the knife 75 being inclined to the horizontal, gravity feeding means comprising a chute for guiding the object to be sliced past the cutting knife to effect the cutting operation in a direction substantially perpendicular to the plane of the knife, and means for guarding the edge of said knife for a major portion of its periphery.

6. The combination, of a cutting mechanism, comprising a knife edge which is 85 moved during the cutting operation, the plane of which is inclined to the horizontal, guiding means for gravity feeding the object to be sliced in a direction inclined to the horizontal past the cutting knife, and 90 means for varying the thickness of the slices, the guiding means being reciprocal in a rectilinear direction.

7. The combination of a cutting mechanism comprising a knife edge, the plane of which is inclined to the horizontal, movable 95 guiding means for feeding the object to be sliced by its own weight in a direction inclined to the horizontal past the knife edge, the guiding means being free from clamping elements, and a table, the surface of the 100 table lying substantially in the same plane as the knife edge, and means for changing the position of said table with respect to the knife edge.

8. The combination of a cutting mechanism comprising a rotary knife edge, the plane of which is inclined to the horizontal, means comprising a chute for guiding the object to be sliced in a direction inclined to the horizontal to the cutting edge, a 110 tiltable tray, the surface of the tray lying substantially in the same plane as the plane of the knife edge, and means for changing the elevation of one end of said tray with respect to the cutting edge.

9. The combination of a cutting mechanism comprising a rotary knife edge, the plane of which is inclined to the horizontal, means for guiding the object to be sliced 115 in a direction inclined to the horizontal to the cutting edge, a tray, the surface of the tray lying substantially in the same plane as the plane of the knife edge, and a cam bearing against the lower surface of said tray for changing the elevation of said tray with respect to the cutting edge.

10. The combination of a cutting mechanism comprising a rotary knife edge, the plane of which is inclined to the horizontal,

means for guiding the object to be sliced in a direction inclined to the horizontal to the cutting edge, a tilttable tray the surface of the tray lying substantially in the same 5 plane as the plane of the knife edge, and a cam, the face of which bears against the lower surface of said tray, for changing the elevation of one end of said table with respect to the cutting edge.

10 11. A mechanism for regulating the thickness of slices in a disc knife slicing machine comprising a tilttable tray, a rotatable cam, the face of which bears directly against the lower surface of one end of said tray, for 15 elevating the end of said table, and means for rotating said cam.

12. A mechanism for regulating the thickness of slices in a meat slicing machine, comprising a rotary disc, a movable tray, and 20 means bearing against the lower surface of said tray to change the elevation of one end of the tray.

13. Means for guarding the cutting mechanism of slicing machines, comprising a stationary post, a stationary disk secured to the post, and a guard plate secured to the 25 said disk.

14. A cutting mechanism for a meat slicing machine, comprising a stationary post, a 30 stationary disc secured to said post, a rotatable disc and a narrow annular continuous blade detachably secured to the periphery of said disc.

15. A cutting mechanism for a slicing 35 machine, comprising a stationary post, a disc rotatably mounted on said post, a narrow annular continuous knife edge, detachably secured to the periphery of said disc, and stationary means substantially co-extensive with said disc and knife edge, for 40 guarding said knife edge.

16. A cutting mechanism for a slicing machine, comprising a stationary post, a disc 45 rotatably mounted on said post, a narrow annular continuous knife edge detachably secured to the periphery of said disc, and stationary means, substantially co-extensive with said disc and knife edge, for guarding said knife edge the stationary means having an overhanging portion adjacent to said 50 knife edge.

17. A cutting mechanism for a slicing machine, comprising a stationary member, a 55 rotatable knife edge, and means comprising a stationary guard plate for guarding said knife edge, overhanging a major portion of its periphery.

18. A cutting mechanism for slicing machines, comprising a stationary post, a disc 60 rotatably mounted on said post, an annular knife blade secured to the edge of said disc, and means, comprising a stationary plate, substantially co-extensive with said rotatable disc, and having a depending portion overhanging a major portion of the pe- 65

riphery of said knife blade, the overhanging portion guarding the blade, and the stationary plate guarding the rotary disc.

19. In a meat slicing machine, the combination of meat guiding means, arranged to 70 feed the meat in a direction inclined to the horizontal, meat cutting means comprising an annular knife blade having a substantially stationary center of rotation, the plane of which is inclined to the horizontal and is located perpendicular to the direction of feed of the meat guiding means, an adjustable tray, the plane of which is located in the same plane as the plane of the knife edge, and means for changing the elevation 75 of said tray with respect to the knife edge.

20. In a meat slicing machine, the combination of meat guiding means, arranged to 80 feed the meat in a direction inclined to the horizontal and movable past a portion of the cutting edge, meat cutting means comprising an annular knife blade, the plane of which is inclined to the horizontal and is located perpendicular to the direction of feed of the meat guiding means, an adjustable tray, the plane of which is located in the same plane as the plane of the knife edge, and a cam, the surface of which bears 85 against the lower surface of said tray, for changing the elevation of said tray with respect to the knife edge.

90 21. The combination in a slicing machine of a rotary cutting knife, the plane of which is inclined to the horizontal, and means for guiding the object to be sliced in a direction inclined to the horizontal to the cutting knife, said means being arranged to oscillate in a direction substantially parallel to the plane of the cutting knife.

95 100 22. The combination in a slicing machine of a rotary cutting knife, the plane of which is inclined to the horizontal, means for guiding the object to be sliced in a direction inclined to the horizontal to the cutting knife, said means being arranged to oscillate 105 in a direction substantially parallel to the plane of the cutting knife, and means for normally urging the guiding means in one direction.

110 115 23. The combination in a slicing machine of a rotary cutting knife, the plane of which is inclined to the horizontal, means for guiding the object to be sliced in a direction inclined to the horizontal to the cutting knife, said means being arranged to oscillate in a direction substantially parallel to the plane of the cutting knife, and a counter-weight for normally urging the guiding means in one direction.

120 125 24. The combination in a slicing machine of a rotary cutting knife, the plane of which is inclined to the horizontal, a chute for guiding the object to be sliced, to the cutting knife in a direction substantially perpendicular thereto, and a pivoted arm sup- 130

- porting said chute whereby the chute may be oscillated past the effective edge of the cutting knife.
25. The combination in a slicing machine of a rotary cutting knife, the plane of which is inclined to the horizontal, a chute for guiding the object to be sliced to the cutting knife in a direction substantially perpendicular thereto, a pivoted arm supporting said chute, whereby the chute may be oscillated past the effective edge of the cutting knife, and means for normally urging the chute in one direction.
26. The combination in a slicing machine of a rotary knife, the plane of which is inclined to the horizontal, a chute for guiding the object to be sliced to the cutting knife in a direction substantially perpendicular thereto, a pivoted arm supporting said chute, whereby the chute may be oscillated past the effective edge of the cutting knife, and a counter-weight secured to said arm.
27. A slicing apparatus comprising a knife edge, a chute down which the object to be sliced slides freely by its own weight, the chute being free from clamping elements and an adjustable gauge tray having a cut-away portion to regulate the thickness of the slices.
30. 28. A slicing apparatus comprising a knife edge and a reciprocative chute inclined from the vertical down which the object to be sliced is adapted to slide freely by its own weight and an adjustable gauge tray having a cutaway portion to receive the knife.
29. In a slicing machine, the combination with a rotary knife, of an oscillatably mounted gravity-feed holder in operative relation therewith.
30. In a slicing machine, the combination with a rotary knife, of a gravity-feed holder, and means comprising a slidable member for mounting said holder so that the same may be moved back and forth with respect to the knife.
31. In a slicing machine, a support, a shaft journalled on the support, shaft rotating means, a knife fixed to the shaft for rotation therewith an arm pivoted to the support, a receptacle inclined to the vertical fixed to the arm and adapted to retain the article to be sliced, said arm and receptacle adapted to be swung toward and from the knife.
32. A meat slicing apparatus comprising a movable knife edge which moves during the cutting operation and a reciprocative chute inclined from the vertical down which the object to be sliced slides freely by its own weight.
33. A meat slicing apparatus comprising a circular knife edge, an inclined chute and a table to regulate the thickness of the slices having a circular cut away portion to receive the knife edge.
34. In a slicing machine the combination with a rotary knife, of a gravity feed holder having one side open to receive the object and means for mounting said holder so that the same may be moved back and forth with respect to the knife.
- In witness whereof, I have hereunto signed my name.

PETER SIVERTSEN.

porting said chute whereby the chute may be oscillated past the effective edge of the cutting knife.

25. The combination in a slicing machine of a rotary cutting knife, the plane of which is inclined to the horizontal, a chute for guiding the object to be sliced to the cutting knife in a direction substantially perpendicular thereto, a pivoted arm supporting said chute, whereby the chute may be oscillated past the effective edge of the cutting knife, and means for normally urging the chute in one direction.

26. The combination in a slicing machine of a rotary knife, the plane of which is inclined to the horizontal, a chute for guiding the object to be sliced to the cutting knife in a direction substantially perpendicular thereto, a pivoted arm supporting said chute, whereby the chute may be oscillated past the effective edge of the cutting knife, and a counter-weight secured to said arm.

27. A slicing apparatus comprising a knife edge, a chute down which the object to be sliced slides freely by its own weight, the chute being free from clamping elements and an adjustable gauge tray having a cut-away portion to regulate the thickness of the slices.

30 28. A slicing apparatus comprising a knife edge and a reciprocative chute inclined from the vertical down which the object to be sliced is adapted to slide freely by its own weight and an adjustable gauge tray having a cutaway portion to receive the knife.

29. In a slicing machine, the combination with a rotary knife, of an oscillatably

mounted gravity-feed holder in operative relation therewith.

30. In a slicing machine, the combination with a rotary knife, of a gravity-feed holder, and means comprising a slideable member for mounting said holder so that the same may be moved back and forth with respect to the knife.

31. In a slicing machine, a support, a shaft journalled on the support, shaft rotating means, a knife fixed to the shaft for rotation therewith an arm pivoted to the support, a receptacle inclined to the vertical fixed to the arm and adapted to retain the article to be sliced, said arm and receptacle adapted to be swung toward and from the knife.

32. A meat slicing apparatus comprising a movable knife edge which moves during the cutting operation and a reciprocative chute inclined from the vertical down which the object to be sliced slides freely by its own weight.

33. A meat slicing apparatus comprising a circular knife edge, an inclined chute and a table to regulate the thickness of the slices having a circular cut away portion to receive the knife edge.

34. In a slicing machine the combination with a rotary knife, of a gravity feed holder having one side open to receive the object and means for mounting said holder so that the same may be moved back and forth with respect to the knife.

In witness whereof, I have hereunto signed my name.
